Int. Cl. D25—03

U.S. Cl. D30—1

FIG. 1 is a perspective view of an A-frame poultry cage shelter showing my new design, an intermediate portion being broken away and omitted to indicate indeterminate length;

FIG. 2 is a reduced scale top plan view; and

FIG. 3 is a cross-sectional view taken along line 3—3 of FIG. 1.

This application is a continuation-in-part of design application Ser. No. 149,093, filed June 1, 1971, now Patent Des. 228,557.

I claim:

The ornamental design for an A-frame poultry cage shelter, as shown and described.
